DESIGN.

—o—

H. W. GEBAUER & W. H. JOHNSON.
LOCK TRIMMING.

No. 19,505.

Patented Dec. 17, 1889.

UNITED STATES PATENT OFFICE.

HENRY W. GEBAUER AND WILLIAM H. JOHNSON, OF CLEVELAND, OHIO,
ASSIGNORS TO THE PERKINS LOCK MANUFACTURING COMPANY, OF
SAME PLACE.

DESIGN FOR A LOCK-TRIMMING.

SPECIFICATION forming part of Design No. 19,505, dated December 17, 1889.

Application filed November 18, 1889. Serial No. 330,804. Term of patent 7 years.

To all whom it may concern:

Be it known that we, HENRY W. GEBAUER and WILLIAM H. JOHNSON, citizens of the United States, residing at Cleveland, in the 5 county of Cuyahoga and State of Ohio, have invented and produced a new and original Design for Lock-Trimming, of which the following is a specification, reference being had to the accompanying drawing, forming part 10 thereof.

The figure is a view in perspective.

The leading features of our new design are, first, groundwork of raised flowers on lock-front, escutcheon, and knob; second, a border 15 of raised work representing a cable extending around the edges of lock-front and escutcheon; third, a funnel-shaped concavity located at the center of the knob-face, the walls of such concavity being ribbed and terminating in a button or acorn at the apex, and having raised work representing a cable extending around the base of such concavity.

A represents the lock-front, having groundwork *a* of raised flowers, and having a cable 20 border *a'*.

B represents the escutcheon, the same having groundwork *b* of raised flowers, and a cable border *b'*.

C represents the knob, the same having 25 raised work at *C'* representing flowers, and having a funnel-shaped depression at *c*, the

walls thereof being ribbed at *c'* and terminating in a button or acorn *c''*. Raised work representing a cable *c'''* extends around the base of the funnel-shaped depression. 35

What we claim is—

1. In a design for lock-trimmings, the lock-front, the face of which is ornamented with a groundwork of raised flowers, as shown.

2. In a design for lock-trimmings, the ornamentation of the escutcheon-plate, consisting of a groundwork of raised flowers surrounded by raised work representing a cable, 40 as shown.

3. In a design for lock-trimmings, the ornamentation of the knob, consisting of a funnel-shaped depression at the center of the face of the knob, the walls of such depression being ribbed and terminating in a button or acorn at the apex of the depression, 45 and a raised work representing flowers around the face of the knob outside of the depression, as shown.

In testimony whereof we sign this specification, in the presence of two witnesses, this 50 21st day of August, 1889.

HENRY W. GEBAUER.
WILLIAM H. JOHNSON.

Witnesses:

CHAS. H. DORER,
H. S. FRENCH.
